UNITED STATES PATENT OFFICE.

HENRI JEAN JOSEPH MARIE DE REGNAULD DE BELLESCIZE, OF TOULON, FRANCE.

FILTER FOR HIGH-FREQUENCY OSCILLATIONS.

Application filed June 2, 1923, Serial No. 642,883, and in France June 8, 1922.

The present invention relates to an improved method of coupling a plurality of resonant circuits cascade fashion, and more particularly relates to securing a purely inductive coupling between such circuits. My invention is illustrated in the attached drawing in which

Fig. 1 shows an arrangement of tuned circuits in cascade as used in radio signalling systems,

Fig. 2 shows a similar system as constructed in accordance with my invention,

Fig. 3 shows such a system provided with a closed antenna, and

Fig. 4 is a comparison of resonance curves of the old and new arrangement.

The disposition in cascade of several tuned or resonant circuits has been resorted to for a long while in the construction of receiving apparatus in wireless work. This arrangement which at equal syntony, permits of reducing the duration of establishment and extinction of oscillations, shows a tendency of becoming more general in use and application under the name of "filters". Now, in order to realize good results it is indispensable that the coupling existent between the two consecutive resonators, no matter of what sort they may be, should not be at the same time inductive and electrostatic (or capacitative).

In Fig. 2 of the drawing in which is illustrated, by way of example, my invention applied to a filter, C_0 represents a conventional aerial connected to ground through the inductance L_0 and the coil m . The coil m is in inductive relation to the coil M to induce oscillations, corresponding to those in the antenna circuit, in the resonant circuit M, C_1 . This latter circuit is inductively connected in cascade to the resonant circuit L_2, C_2 , which in turn is inductively coupled to the resonant circuit L_3, C_3 . The relation of the coupling coils in each of these circuits is exactly similar, and it will be necessary to describe the arrangement with respect to the circuit M, C_1 alone.

The coupling coils m, M are placed end to end in inductive relationship and their adjacent ends are grounded to fix the potential at these points. That is, the point O in the coil M is grounded and the point o in the coil m is grounded. From this arrangement it follows that the potential between ground and any point in the coil M is proportional to the distance between that

point and the coil m . In other words, the higher the potential of a point in the coil M above ground potential, the greater will be its distance from the coil m and as the capacity between the coils is inversely proportional to the distance separating them the capacitative effects along coil M decrease as the potential increases, thereby reducing the capacitative coupling between the coils M, m to a minimum.

The arrangement in Fig. 3 is substantially the same as that in Fig. 2, except that the aerial C_0 is replaced by a closed antenna circuit comprising the inductance L_0 and the condenser C_0 . The operation of this device is, of course, the same as that of the device shown in Fig. 2.

Owing to this arrangement, when the period of excitation at the input end of the filter device is caused to be varied, the resonance curve observed at the output end assumes the regular shape of curve a (Fig. 4); whereas when cutting off the various equipotential connections previously described (which substantially is tantamount to the employment of the customary mode of mounting as illustrated in Fig. 1), a curve is obtained having a shape substantially as curve b , Fig. 4.

The input resonator, i. e., resonant circuit, may consist of either an open or a closed antenna (Fig. 2 and Fig. 3 respectively). The resonators, with the exception of the antenna, can be enclosed in a metal cage X , which shields and protects them from the direct action of Hertian waves. The said metallic box could also be subdivided or partitioned by means of partitions Y likewise consisting of metal, to the end of enclosing each coil L in its own Faraday cage, which safeguards it from residual or stray electrostatic actions due to other coils. The cages themselves could be earthed.

The invention itself, be it well understood, is not confined to the modes of execution as hereinbefore described by way of example; more particularly it is susceptible of comprising all supplementary devices susceptible of diminishing the capacity effects between windings, or between windings and the ground.

Having described my invention, what I claim is:

1. In a filter arrangement, a plurality of inductively coupled resonant circuits, each of said circuits having a primary and a

secondary coupling coil, the primary one of said circuits being connected end to end with the secondary of the next successive circuit, and a ground connection joined to each common connection of the primary and secondary.

2. In a cascade circuit arrangement, a plurality of resonant circuits, each having primary and secondary inductance coils, one end of each primary and its associate secondary in the next successive resonant cir-

cuit being connected to a common ground, the arrangement being such that the potential at any point in said inductances is directly proportional to the distance between said point and the common ground connection, thereby substantially reducing the distributive capacity between said primary and secondary inductance coils. 15

HENRI JEAN JOSEPH MARIE de
REGNAULD de BELLESCIZE.
